FIG. 3.

FIG. 4.

FIG. 5.

Fig. 1 is a perspective view of a combination earth roller and tractor showing my new design.

Fig. 2 is a front elevational view thereof.

Fig. 3 is a side elevational view thereof.

Fig. 4 is a rear elevational view thereof.

Fig. 5 is a top plan view thereof.

The dominant features of my design reside in the portions shown in full lines, said portions being characterized by the two large rollers on the sides and the two smaller rollers on the front having the configurations shown.

I claim:

The ornamental design for a combination earth roller and tractor, as shown and described.
